AUTOMATIC CIRCUIT BREAKER

Kurt Walter Wilckens, Morrisville, Pa., assignor to Heine-mann Electric Company, Trenton, N. J., a corporation of New Jersey

Application December 14, 1951, Serial No. 261,672

9 Claims. (Cl. 200—106)

My invention is a trip-free circuit breaker designed to minimize the lag between a deleterious flow of current, such as a short circuit, and the interruption of the circuit through which the current flows.

My invention is preferably embodied in a circuit breaker which will not only interrupt a circuit instantaneously upon the occurrence of a short circuit or over-load which is immediately deleterious, but will also interrupt the circuit upon the occurrence of lesser over-loads before the heat generated thereby becomes seriously deleterious and after a delay timed relatively to the intensity of the overload, and which will permit such momentary overloads as are incident to starting a motor, turning on lights, etc.

A leading object of my invention is the simplification of the mechanism through which the energy of an over-load is utilized to effect the interruption of the circuit, and in the preferred embodiment of my invention this energy is utilized to create a magnetic flux which actuates an armature mounted directly upon, and controlling, a collapsible linkage by which a biased switch blade is normally held in closed position.

The switch blade is pivotally connected with one end of the collapsible linkage, whose other end may be pivotally supported by a handle by which the switch blade may be manually opened or closed when the linkage is in stress-transmitting position.

The linkage is preferably held against collapse, and in stress-transmitting position, by complementary latch members on the respective links of the linkage and one of which members is operable by the armature when the flux intensity becomes sufficient to attract the armature across an air gap between the armature and the pole or poles of an electro-magnet having a coil in circuit with the switch blade.

The flux acting on the armature may be intensified relatively to the current flow by utilizing an electro-magnet whose internal magnetic circuit may be fully closed by permeable material upon the long continuance of the minimum overload at which tripping is desired, or which may be interrupted by a gap of varying length upon the flow of greater overloads of lesser duration. The maximum air gaps prevail during current flow at rated capacity. The poles of such a magnet are preferably bent so as to bring bifurcated ends of each pole into juxtaposition with the armature when the switch blade is closed. When the armature is thus disposed, portions thereof may move between the bifurcations to permit other portions of the armature to rock toward and into contact with other portions of the poles.

The attraction of the armature by the flux effects the unlatching of the linkage to permit biasing of the switch blade and handle to open position. Thereafter the links and latch are biased into locked position to permit the transmission of stress from the handle to the switch blade to effect the closure of the latter under pressure.

The switch blade may, of course, be opened or closed by manually operating the handle without unlatching the latch and links, but so long as there is sufficient overload potential across the switch blade, it cannot be held in closed position by manipulating the handle, since magnetic flux will be generated and effect the release of the latch as soon as the overload flows through the switch and electro-magnet.

The principles of my invention, and the best mode in which I have contemplated applying such principles, will

2

further appear from the following description and the accompanying drawings in illustration thereof.

In the drawings Fig. 1, is an enlarged side elevation of a circuit breaker embodying my improvements, with parts broken away to show the interior construction; Fig. 2 is a fragmentary view illustrating the movement of the armature to position for unlatching the linkage latch, the linkage not yet having collapsed; Fig. 3 is a detached, perspective view of the linkage, latch and armature, with part broken away to show the latch elements in latching positions; Fig. 4 is a side elevation of the circuit breaker, with parts broken away, and showing the parts in open position ready for re-closing by manipulating the handle; Fig. 5 is an exploded, perspective view of the linkage, latch and armature; and Fig. 6 is an irregular, sectional view taken on the line 6—6 of Fig. 1.

In the embodiment of my invention illustrated in the drawings, a magnetically permeable bracket 1 is secured by bolts 2 to the base of a hollow insulating housing 3. The bracket 1 is provided with a pair of spaced ears 4 containing elongated slots 5 having walls forming elongated fulcrums for a pintle which passes through an elongated diagonal slot in a switch blade 7. The switch blade 7 has a contact 8 movable into and out of engagement with a yielding contact 9 of a terminal 10 which is secured to the base of the housing 3 by a screw 11. The contact 9 may be connected by a conducting strip 12 with an external line terminal 13.

The switch blade 7 is normally biased toward open position by a bifurcated spring 14, which has a bight 15 looped across the shank of the switch blade, and has legs wound around the pintle 6 and ends engaging the bracket 1.

The switch blade 7 is operable by means of a pivoted handle 16 through linkage comprising links 17 and 18 respectively pivotally connected by pintles 19 and 20 with the handle 16 and switch blade 7 and pivotally connected with one another by a pintle 21. The links 18 have an adjustable lip 22 overlying the link 17, which permits the collapse of the linkage in one direction but limits the movement of the links around the pintle 21 in the reverse direction.

The linkage may be latched against collapse by the engagement of teeth 23 (Figs. 3, 5) on the links 17 with the peripheral surface of a shaft 24, journaled in the links 18, and having an armature 25 fixed thereto between the links. The shaft 24 is cut away, intermediate its ends, to form on either side of the armature, a recess or radial slot 26 of sufficient width and depth to permit the passage of a tooth 23 when the armature 25 and shaft 24 are turned anti-clockwise to bring the slots 26 into registration with the teeth 23.

The armature 25 is normally biased, to move the peripheral surface of the shaft 24 into position for engagement by the teeth 23, by a spring 27, which is coiled around the pintle 21 and has one end engaging a tooth 28 on the armature 25 and its other end anchored under the pintle 19.

Clockwise movement of the shaft 24 is limited by the engagement of a stud 30 on the armature 25 with a stop 29 projecting from the link 18.

The armature 25 is composed of readily permeable material, such as soft iron, and depends from the shaft 24 below the linkage into the path of magnetic flux flowing between the bifurcated poles 31 and 32 of an electromagnet, which includes a non-magnetic tube 33 seated in an aperture in the magnetically permeable bracket 1 and solenoid coil 34 encircling the tube.

One end of the coil 34 is connected, through the pigtail 35, with the switch blade 7. The other end of the coil 34 is connected through the conductor 36 with an external load terminal 37.

The pole piece 31 forms a part of the bracket 1, and the pole piece 32 is fixed to a magnetically permeable closure 38 at the outer end of the tube 33. The inner end of the tube 33 communicates, through an opening in the bracket 1, with the non-magnetic cap 39, fixed to the bracket 1 and forming a chamber of larger cross-sectional area than the cross-section of the passage through the tube 33.

A magnetically permeable core 40 is movable recti-

linearly in the tube 33 and cap 39 against the resistance of a coiled spring 41 and of a fluid, or a thermally-fusible solid, sealed in the tube 33 and cap 39 to provide a dashpot action.

The core 40 has enlarged head 42 and a reduced nose 43 for making close magnetic contact with the bracket 1 and closure 38, respectively, when the core is drawn into the solenoid coil 34 to its maximum extent, thereby decreasing the reluctance of the internal circuit of the magnet by closing or shortening air gaps therein.

The armature 25 is so shaped and positioned that the poles 31 and 32, when energized, both exert a tractive force thereon in the same direction, viz., in an anti-clockwise direction in the position shown in Fig. 1. This may be accomplished by slotting the pole so that the bulge 25a is movable therein until the skirt 25b is in close juxtaposition to or contact with the vertically inclined face of the space between and below the bifurcations of the pole 31.

The pole 32 is more deeply slotted than the pole 31, and the bulge 25c of the armature 25 lies therein so that upon anti-clockwise movement of the armature its bottom surface comes into relatively close juxtaposition to or contact with the substantially horizontal top surface of the pole piece 32.

When the terminals 13 and 37 are connected in circuit and the switch blade 7 is closed against the contact 9, current flows through the coil 34. The coil has such number of ampere turns that the magnetic flux created thereby, on the flow of rated current, exerts insufficient attraction on the core 40 to overcome the resistance of the spring 41 and the dash pot fluid. When the current flow rises toward 125% of rated capacity, the flux generated by the coil moves the core 40 into the coil 34 at a rate proportionate to the overload. When the overload approaches 125% of rated capacity, the head 42 and the nose 43 will eventually contact the bracket 1 and closure 38, thereby decreasing the reluctance of the magnetic circuit between the members 1 and 38 and increasing the magnetic flux between the pole pieces 31 and 32 and through the armature 25.

This increase in flux causes the armature 25 to rock and anti-clockwise between the pole pieces 31 and 32 and thereby move the shaft 24 so that slots 26 register with and permit the passage of the teeth 23, as indicated in Fig. 2. This permits the links 17 and 18 to collapse around the pintle 21 under the biasing action of the spring 14 on the switch blade 7, with consequent opening of the switch blade 7 and rocking of the handle 16 into open position as shown in Fig. 4. The movement of the handle 16 into open position (Fig. 4) straightens the links 17 and 18 and causes the spring 27 to act on the tooth 28 and rock the armature 25 and shaft 24 into such position that the teeth 23 engage the peripheral surface of the shaft 24. The switch blade 7 may be closed by manually rocking the handle 16 about its pivot.

The interruption of the circuit between the contact 9 and contact 8 of the switch blade 7 interrupts the flow of energizing current through the coil 34. The spring 41 thereupon expands and moves the core 40 back to its original position. When current flows in the coil 34 at a rate of or in excess of, the permissible overload of 125%, the core is moved faster than before toward the closure 38, and the flux generated will flow between the pole pieces 31 and 32 through the armature 25 at a density sufficient to rock the latter into unlatching position before the nose 43 contacts the closure 38.

In the event of a short circuit, the flux density generated is sufficient to rock the armature 25 before any substantial movement of the core 40 takes place and tripping stress is thus applied to the armature 25 substantially concurrently with the rise of the current flow in the coil 34, without the lag incident to the inertia and play of usual armature and tripping mechanisms.

Having described my invention I claim:

1. A circuit breaker comprising a switchblade, collapsible linkage having one end connected with said switchblade and through which said switchblade is closable, a support for the other end of said linkage, a latch for holding such linkage in stress transmitting position, an armature connected with said latch and movable by said linkage, said latch and armature being supported solely by said linkage, and an electro magnet in circuit with said switchblade and having a pole adjacent to said armature when said linkage is in stress transmitting position.

2. An overload circuit breaker comprising a switch-

blade, a handle for operating said switchblade, collapsible linkage connecting said switchblade and handle, means including a mechanical latch for holding said linkage in stress transmitting position, an armature supported solely

5 by and movable with said linkage and operatively associated with said means, and an electro magnet in circuit with said switchblade and energized by current flowing therethrough to attract said armature and therethrough actuate said means to permit the collapse of said linkage.

10 3. A circuit breaker comprising a switchblade, collapsible linkage having one end connected with said switchblade and through which said switchblade is closable, a support for the other end of said linkage, a shaft journaled in said linkage and forming a latch member, an armature depending from such shaft and an electro magnet in circuit with said switchblade and having a pole adjacent to said armature in the stress transmitting position of said linkage.

15 4. A circuit breaker comprising a switchblade, collapsible linkage having one end pivotally connected with said switchblade, a support for the other end of said linkage, said linkage comprising links having complementary latch members thereon respectively, an armature pivotally connected with and supported solely by said linkage and having means engageable with one of said latch members, and an electro magnet responsive to current flowing through said switchblade and having a pole adjacent to said armature when said linkage is in stress transmitting position.

20 5. A circuit breaker comprising a switchblade, linkage having one end pivotally connected with said switchblade, a support for the other end of said linkage, a latch controlling said linkage and including a shaft journaled in said linkage, an armature supported solely by said shaft and movable to operate said latch, means for biasing said shaft in one direction, a stop limiting the biasing action of said means and an electro magnet having a pole positioned adjacent to said armature for moving it contra said biasing means.

25 6. A circuit breaker comprising a switchblade, collapsible linkage having one end pivotally connected with said switchblade, a support for the other end of said linkage, the collapse of said linkage permitting movement of said switchblade, an armature supported solely by and controlling the collapse of said linkage, and an electromagnet electrically connected with said switchblade and having a bifurcated pole piece adjacent to said armature.

30 7. A circuit breaker comprising a switchblade and means for controlling the position of said switchblade, said means including an electromagnet having a coil connected with said switchblade and pole pieces each having a section extending substantially parallel with the axis of said coil and sections extending transversely to the axis of said coil, one of the transverse sections of each pole piece being bifurcated, an armature pivotally connected with and moved by the movement of said switchblade, said armature being positioned between the bifurcations of said sections when said switchblade is in closed position, and a latch operable by said armature to permit the movement of said switchblade to open position.

35 8. A circuit breaker comprising a switchblade and means for controlling the position of said switchblade, said means including an electromagnet having a bifurcated pole piece, an armature pivotally connected with and moved by the movement of said switchblade, said armature having a nose movable between said bifurcations when said switchblade is closed to permit the approach of a portion of said armature toward an unbifurcated portion of said pole piece, and a latch operable by the movement of said armature to release said switchblade from its closed position.

40 9. A circuit breaker comprising a switchblade, collapsible linkage having one end pivotally connected with said switchblade and through which said switchblade is closable, an electromagnet having a coil and opposite pole pieces extending transversely to the axis of said coil, an armature supported by said linkage in juxtaposition to both said pole pieces in the closed position of said switchblade and movable by said linkage away from at least one of said pole pieces upon the opening of said switchblade, and a latch operable by said armature for controlling said linkage.
